UNITED STATES PATENT OFFICE.

JACOB MARCUS, OF PHILADELPHIA, PENNSYLVANIA.

DESIGN FOR A SIGN-PLATE.

SPECIFICATION forming part of Design No. 31,832, dated November 14, 1899.

Application filed October 19, 1899. Serial No. 734,129. Term of patent 7 years.

To all whom it may concern:

Be it known that I, JACOB MARCUS, a citizen of the United States, residing at Philadelphia, in the county of Philadelphia, State of Pennsylvania, have invented and produced a new and original Design for a Sign-Plate or Similar Article, of which the following is a specification, reference being had to the accompanying drawings, forming part thereof,

o in which—

Figure 1 is a face view of a sign-plate bearing and incorporating my design, and Fig. 2 is an edge view of the same.

The leading feature of my design consists of the clouded ornamentation in portions of the main face of the substantially flat plate and the border ornamentation along the outer portions of the face of the plate, substantially as shown in the drawings.

In the drawings, A designates the plate, 20 which has a substantially flat face, as shown in Fig. 2, and which face, as illustrated in Fig. 1, bears the ornamental clouds C C in portions thereof extending in irregular outline from a point c' on the border to a point c² 25 on the adjacent border, and the ornamental border B, composed of lines in representation of ribbon.

What I claim is—

The design for a sign-plate or similar article, substantially as shown and described.

In testimony whereof I have signed my name to this specification in the presence of two subscribing witnesses.

JACOB MARCUS.
